HAND GUN CASE

Paul Belokin, Jr., 6919 W. 43rd St.,
Berwyn, Ill. 60402

Filed Mar. 24, 1969, Ser. No. 16,401

Term of patent 14 years

Int. Cl. D3—01

U.S. Cl. D87—1

FIG. 1

FIG. 3

FIG. 2

FIG. 4

FIG. 5

FIG. 6

FIG. 1 is a top plan view of a hand gun case, showing my new design;

FIG. 2 is a side elevational view, the opposite side being substantially a mirror image thereof;

FIG. 3 is a barrel end elevational view;

FIG. 4 is a cover end elevational view;

FIG. 5 is a bottom plan view; and

FIG. 6 is a perspective view thereof with the cover unlatched and partly open.

I claim:

The ornamental design for a hand gun case, as shown and described.
